UNITED STATES PATENT OFFICE.

ALAN ROBB FERGUSSON, OF BALTIMORE, MARYLAND, ASSIGNOR TO HENRY F. MILLER AND GEORGE MILLER, OF SAME PLACE.

BOX OR CAN.

SPECIFICATION forming part of Letters Patent No. 604,975, dated May 31, 1898.

Application filed October 9, 1897. Serial No. 654,655. (No model.)

To all whom it may concern:

Be it known that I, ALAN ROBB FERGUSSON, of Baltimore, in the State of Maryland, have invented certain new and useful Improvements in Boxes or Cans; and I do hereby declare the following to be a full, clear, and exact description of the invention, such as will enable others skilled in the art to which it appertains to make and use the same.

10 My invention relates to an improvement in boxes or cans for containing and dispensing material in measured quantities, the object of the invention being to provide a simple, cheap, and efficient device whereby material contained in a box or receptacle can be measured and discharged easily and quickly and without waste.

15 A further object is to so construct the valved outlet of a box or can as to keep the same normally tight.

20 With these objects in view the invention consists in certain novel features of construction and combinations and arrangements of parts, as hereinafter set forth, and pointed out in the claims.

25 In the accompanying drawings, Figure 1 is a view of a can or receptacle having my improvements applied thereto. Fig. 2 is a sectional view. Fig. 3 is a view of a modification.

30 A represents a box, can, or receptacle for powder or other material, provided at one end with a fixed cover or top B, having a neck C. The neck C is preferably screw-threaded for the reception of a similarly-threaded measurer D.

35 The measurer D is closed at both ends and provided in its vertical wall with a slot or opening 1. When the measurer D is screwed down, the lower portion of the slot or opening will communicate with the interior of

40 the body portion of the box or receptacle, so that powder can flow therefrom into the measurer. When the measurer is in this position, the powder can escape therefrom above the neck. The powder having been made to enter

45 the measurer by inverting the box or receptacle, said measurer will be unscrewed, so as to cause it to move longitudinally and allow the slot or opening therein to extend above the upper end of the neck C. The powder

50 can now be discharged from the measurer and communication between the latter and the body of the box or receptacle will be closed.

In the form of the invention shown in Fig. 3 the neck and measurer are not screw-

threaded, but the measurer is adapted to slide 55 longitudinally, so as to cause the slot or opening therein to communicate with the interior of the box or receptacle or to close such communication and discharge the powder into or onto the device with which it is desired to 60 use it.

My improvements are simple in construction, can be manufactured at small cost, and are effectual in the performance of their functions.

65 Other slight changes might be made in the details of construction of my invention without departing from the spirit thereof or limiting its scope, and hence I do not wish to limit myself to the precise details herein set forth.

70 Having fully described my invention, what I claim as new, and desire to secure by Letters Patent, is—

75 1. The combination with a box or receptacle having a restricted neck, of a measurer mounted in said neck so as to be capable of longitudinal movement therein, said measurer being hollow and closed at both ends and having a slot in its wall adapted to communicate with the interior of the box or receptacle and terminate within the neck when said measurer is closed, and to extend beyond the neck and close communication with the interior of the box or receptacle when the measurer is open, 80 said measurer being constructed to so cooperate with the neck as to limit the extent of movement of the former in both directions.

85 2. The combination with a receptacle and a screw-threaded neck thereon, of a measurer having a corrugated or screw-threaded wall 90 adapted to mesh with the screw-threaded neck, said measurer closed at both ends and having a slot in said corrugated or screw-threaded wall, the neck and measurer being so proportioned relatively to each other that 95 when the measurer is screwed outwardly the slot will project beyond the end of the neck and so that when screwed inwardly the outer end of the slot will be closed and the inner end be in communication with the interior of 100 the receptacle, substantially as set forth.

In testimony whereof I have signed this specification in the presence of two subscribing witnesses.

ALAN ROBB FERGUSSON.
